Thomas Dalton

UNITED STATES PATENT OFFICE.

THOMAS DALTON, OF CHICAGO, ILLINOIS.

MOP-HOLDER.

1,401,051.

Specification of Letters Patent. Patented Dec. 20, 1921.

Application filed March 17, 1921. Serial No. 453,124.

To all whom it may concern:

Be it known that I, THOMAS DALTON, a citizen of the United States, residing at Chicago, in the county of Cook and State 5 of Illinois, have invented certain new and useful Improvements in Mop-Holders, of which the following is a specification.

This invention relates to improvements in mop holders, and more particularly to improved means for detachably securing the 10 mop in the holder. Considerable trouble is usually involved in attaching and removing mops for holders, particularly in removing the mop, as the fabric of a mop 15 in use is liable to become very much entangled so that it is often necessary to cut the mop before it can be removed from the holder. I therefore provide means for avoiding such trouble by making the jaws 20 which clamp the mop detachable, so that when the outer jaw on which the mop hangs is removed, the mop goes with it. Another object is to provide detachable clamping parts so that in case such parts 25 are damaged or broken they can be easily replaced, thus avoiding the necessity of throwing the holder away which is often the case with similar devices of different construction. A further object is to provide 30 means for keeping a wet mop from coming in contact with the threaded stem. When a mop is not in use it is generally placed against a wall, with the mop up, so that a wet mop in that position would 35 hang down and come in contact with the threaded stem, thus causing the stem to corrode and making it difficult to operate the thumb nut. I avoid this by securing a disk on the threaded stem which disk ex- 40 tends outwardly sufficiently to hold the mop away from the stem so it cannot come in contact with it. For a complete understanding of my invention reference is had to the following detailed description and 45 accompanying drawings in which—

Figure 1 is a front view of the mop holder including all of the working parts thereof and showing the clamping jaws slightly apart and with the outer jaw in clamping 50 position;

Fig. 2 is a plan view of the inner jaw looking toward the handle;

Fig. 3 is a similar view of the outer jaw, and

Fig. 4 is a perspective view of the ferrule. Referring to the drawings in which simi-

lar numerals of reference denote similar parts throughout the several views, 3 represents the handle provided at one end with a longitudinally extending aperture 21 as 60 shown by dotted lines in Fig. 1, and a capped ferrule 9 with an opening 19 in its capped portion, as shown in Fig. 4, which opening coincides with the opening or aperture 21 in the handle. Near its apertured 65 end, the handle is provided with a transverse perforation 15, and extending from said perforation, in opposite sides of the handle, are grooves 11, which latter extend lengthwise of the handle toward its aper- 70 tured end, and parallel with each other.

A bail 1 has its central portion securely attached to the handle by a V-shaped bend 20 which passes through the perforation 15, and is bent toward and into the grooves 11, 75 as shown at 26 in Fig. 1, after which it is bent at points 22 to diverge as at 23, and then to extend in parallelism as at 24, and terminating in short right angle bends 25 at oppositely disposed points. This manner of forming the bail leaves an open space between the right angle bends 25, through which the inner clamping jaw 2 can be readily removed.

The inner jaw 2 is detachably and slidably 85 mounted on the outer parallel portions 24 of the bail, and it is provided with an oblong slot 4 at each end, and a longitudinal groove 18 between said slots. The jaw 2 also has a boss 12 at a central point on its 90 inner side to which is secured a threaded stem 7 provided with a thumb nut 8. A disk 6 for the purpose before specified is placed on the threaded stem against the boss 12 and secured thereto by a nut 10. 95 The threaded stem 7 passes through opening 19 in the capped portion of the ferrule 9 shown in Fig. 4, and into the aperture 21 in the handle 3 and moves freely therein. The capped portion of the ferrule forms a 100 bearing for the thumb nut 8 on removing the inner jaw from the bail, or attaching it thereto, the oblong slots 4 provided in said jaw permit it to move freely on the bail, and to pass over the right angle bends 25. 105

The outer clamping jaw 5 is detachably mounted on the bail and provided with a longitudinal groove 17 on one side, and a notch 13 at one end, as shown in Fig. 3. When the outer jaw 5 is in clamping position, as shown in Fig. 1, its grooved side 17 abuts against the right angle bends 25, and 110

its notched end 13 engages one side of the bail adjacent to the right angle bend, as shown at 14 in Fig. 1, and thus prevents the jaw from turning. The jaw may be positioned so that its notch 13 engages either side of the bail. The right angle bends 25 serve as stops to limit the outward movement of jaw 5.

When the thumb nut 8 is turned to the right, the inner jaw 4 and the threaded stem 7 recede until the stem comes in contact with the inner end of the longitudinal aperture 21. A mop can then be placed on the inner jaw and the outer jaw placed on top of the mop. The thumb nut is then turned to the left which causes the jaws to move toward the right angle bends 25, said bends serving as stops to limit the outward movement of jaw 5. Thus, the outer jaw is clamped against the right angle bends and the mop is securely clamped between both jaws. The mop can be quickly removed from the holder by repeating the first operation, that is by turning the thumb nut to the right to retract the inner jaw to effect the release of the outer jaw. The outer jaw can be removed and the mop goes with it, and said jaw can then be easily withdrawn from the mop.

While I have shown and described the preferred embodiment of my invention, it will be understood that minor changes in construction, combination and arrangement of parts, may be made without departing from the spirit and scope of the invention as claimed.

I claim—

1. A mop holder comprising a handle having a transverse perforation adjacent to one end, and diametrically opposite longitudinal side grooves extending from the perforation to said end of the handle, a bail having its side portions seating in the grooves and provided with a transverse connecting portion seating in the perforation, said side portions of the bail also projecting from the aforesaid end of the handle and terminating in inwardly directed lateral bends, inner and outer mop-clamping jaws carried by the bail, the outer jaw abutting against the aforesaid lateral bends of the bail end, and means for adjusting the inner jaw.

2. A mop holder comprising a handle, inner and outer mop-clamping jaws, a supporting frame for said jaws carried by the

handle, said frame having laterally spaced and parallel sides between which the inner jaw is slidably supported, the forward extremities of said frame sides having inwardly directed lateral bends which are spaced from each other to permit insertion of the outer jaw to seat between the frame sides behind said bends and abutting thereagainst, one end of the outer jaw being notched to fit a corresponding frame side, and means for operating the inner jaw.

3. A mop holder comprising a handle, inner and outer mop-clamping jaws, a supporting frame for said jaws carried by the handle, said frame having laterally spaced and parallel sides between which the inner jaw is slidably supported, the forward extremities of said frame sides having inwardly directed lateral bends which are spaced from each other to permit insertion of the outer jaw to seat between the frame sides behind said bends and abutting thereagainst, a screw stem extending rearwardly from the inner jaw and extending into the handle, said handle having an axial opening to seat the rear end of the stem, and a nut screwed on the stem and abutting against the forward end of the handle.

4. A mop holder comprising a handle, inner and outer mop-clamping jaws, a supporting frame for said jaws carried by the handle, means for operating the inner jaw, said means including a screw stem extending rearwardly from said jaw, and a guard plate for said stem back of the inner jaw.

5. A mop holder comprising a handle, inner and outer mop-clamping jaws, a supporting frame for said jaws carried by the handle, said frame having laterally spaced and parallel sides between which the inner jaw seats, the forward extremities of said frame sides having inwardly directed lateral bends which are spaced from each other to permit insertion of the outer jaw between the frame sides behind said bends and abutting thereagainst, the inner jaw having elongated apertures through which the frame sides pass, and said apertures having a length to pass the aforesaid bends to permit removal of said inner jaw from the frame, and means for operating the inner jaw.

In testimony whereof I affix my signature.

THOMAS DALTON.
